UNITED STATES PATENT OFFICE.

GUSTAVE A. LEWIS, OF TROY, NEW YORK.

RIPPING-NEEDLE.

1,098,579.

Specification of Letters Patent. Patented June 2, 1914.

Application filed January 8, 1913. Serial No. 740,068.

To all whom it may concern:

Be it known that I, GUSTAVE A. LEWIS, a subject of the King of Great Britain, residing at Troy, in the county of Rensselaer and State of New York, have invented certain new and useful Improvements in Ripping-Needles; and I do declare the following to be a full, clear, and exact description of the invention, such as will enable others skilled in the art to which it appertains to make and use the same.

This invention relates to improvements in ripping needles for sewing machines.

One object of the invention is to provide a needle of this character having a chisel shaped point adapted to engage and rapidly cut stitches formed by a sewing machine without injuring the fabric.

Another object is to provide an instrument of this character which is designed to take the place of the ordinary sewing needle of the sewing machine and to be operated by the latter.

With these and other objects in view, the invention consists of certain novel features of construction, and the combination and arrangement of parts as will be more fully described and claimed.

In the accompanying drawings: Figure 1 is a perspective view of the head of a sewing machine showing my improved ripping needle applied thereto; Fig. 2 is an enlarged edge view of the ripping needle; Fig. 3 is an enlarged side view thereof; Fig. 4 is an enlarged cross sectional view taken on the line 4—4 of Fig. 3.

My improved ripping needle comprises a body portion 1 which may be cylindrical or other suitable shape for engagement with the socket in the needle bar of a sewing machine in which my improved ripping needle is secured in the same manner as an ordinary sewing needle. On the lower end of the body portion 1 of the needle is a reduced flattened blade 2, the outer end of which is tapered on opposite sides to form a chisel or cutting edge 3 in which is formed an inverted V-shaped notch 4.

The notched edge of the needle provides two sharp thread cutting points 5 which when the needle is operated enter the perforations

formed in the fabric by the stitching needle of the machine when the seam was stitched. The points 5 when thus entering the perforations in the fabric cut the knots or stitches of the thread without injuring the fabric thereby quickly ripping the stitched seam.

It will be understood that the detail views shown in the accompanying drawings are greatly enlarged or exaggerated and are drawn in this manner to more clearly bring out the shape or structure of the cutting edge and points of the needle. It will also be understood that, if desired, the needles may be formed in a variety of sizes.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus particularly described my invention, what I claim is:

As an article of manufacture, the herein described ripping needle for sewing machines comprising a shank having an enlarged cylindrical body portion, a reduced flattened extension forming a continuation of said body portion and providing a cutting blade, the latter having right angular corners and two wide parallel side faces, the lower end of said cutting blade having its flat opposite side faces beveled toward each other and the extremity of the blade, and said beveled portions being formed with a V-shaped notch of less depth than said beveled portion, whereby two oppositely positioned points are formed, and which are separated for the purpose described.

In testimony whereof I have hereunto set my hand in presence of two subscribing witnesses.

GUSTAVE A. LEWIS.
